Primary Examiner — Bridget L Eland*Assistant Examiner* — Lauren D McVey(74) *Attorney, Agent, or Firm* — Berg Hill Greenleaf Ruscitti LLP(57) **CLAIM**

The ornamental design for a support for computer terminals and computer keyboards, as shown and described.

DESCRIPTION

FIG. 1 is a left side view of a support for computer terminals and computer keyboards showing my new design;

FIG. 2 is a bottom view thereof;

FIG. 3 is a top view thereof;

FIG. 4 is a right side view thereof.

FIG. 5 is a front view thereof; the rear view being a mirror image thereof; and,

FIG. 6 is a top perspective view thereof.

The outermost broken lines immediately adjacent the claim represent the bounds of the claimed design while all other broken lines are directed to environment and are for illustrative purposes only; the broken lines form no part of the claimed design. In addition, the unshaded surface in the FIG. 2 view that directly adjoins the claimed solid line edge of the center circle forms no part of the claimed design.
